UNITED STATES PATENT OFFICE.

JOHN ZIEGMAN, OF FOSTORIA, OHIO.

DESIGN FOR A BROOM-HOLDER.

46,489.

Specification for Design.

Patented Sept. 29, 1914.

Application filed July 1, 1914. Serial No. 848,491. Term of patent 14 years.

To all whom it may concern:

Be it known that I, JOHN ZIEGMAN, a citizen of the United States, residing at Fostoria, in the county of Seneca and State of Ohio, have invented a new, original, and ornamental Design for Broom-Holders, of which the following is a specification, reference being had to the accompanying drawing, forming part thereof.

The figure is a perspective view of the broom-holder showing my new design.

I claim:

The ornamental design for a broom holder, as shown.

JOHN ZIEGMAN.
